SELECTIVE SIGNALING DEVICE.

1,101,679.

Specification of Letters Patent. Patented June 30, 1914.

Application filed April 1, 1913. Serial No. 758,233.

To all whom it may concern:

Be it known that I, JOHANNES P. C. BOSWAU, a subject of the Emperor of Germany, residing at New York city, in the county 5 and State of New York, have invented a certain new and useful Improvement in Selective Signaling Devices, of which the following is a full, clear, concise, and exact description.

10 This invention relates to selective signaling devices and more particularly to a step by step selective circuit closing device operated in response to a certain predetermined character and combination of current impulses to close a signaling circuit.

15 The object of this invention is to provide a selective signaling device of this class by means of which a very large number of way stations connected with the same line 20 wires may be selectively signaled by means of a relatively small number of current impulses.

In a selective signaling device embodying 25 this invention there is provided a step by step element which is advanced a predetermined distance by current impulses through a stepping and a holding magnet, means being provided for retaining the step by step element in its advanced position during 30 a period of absence of current from the line and subsequently advancing it from its held position to a position where it closes a signaling contact. More specifically this feature consists in the provision of a holding 35 device controlled directly by one of the electro-magnets to engage means carried by said step by step element only when said element has been advanced into a predetermined position and current has been cut off the line.

40 In the drawings illustrating this invention, Figure 1 is a front elevation with parts broken away of a selector embodying this invention, Fig. 2 is a detail view of the step by step element and associated parts, 45 and Fig. 3 is a circuit diagram showing schematically a selector embodying this invention connected therewith.

In the drawings 1 designates a base upon 50 which is mounted an inverted U-shaped frame having side members 2, 2 and a top member 3. Suspended from the top member 3 of the frame are two electromagnets 5 and 6 each comprising two coils. Pivotaly supported near the lower end of the U- 55 shaped frame are armatures 14 and 15, the

armature 14 being responsive to electromagnet 5 and the armature 15 being responsive to electromagnet 6, said electromagnet 6 being made slow acting as clearly indicated in Fig. 3. The armatures 14 and 15 60 are provided with arms 25 and 26 respectively which are brought out through openings in the frame and are extended upwardly along the end of the frame. Attached to the upwardly extending arm 25 is 65 an arm 27 carrying at its upper end a pivotally mounted spring pressed pawl 28 adapted in the movement of the armature 14 to engage the teeth of a ratchet wheel 29 carried in an auxiliary frame 30 mounted 70 upon the U-shaped frame. A holding pawl 31 mounted upon the frame of the selector is adapted to be drawn into engagement with the ratchet wheel 29 by the action of a spring 32. Secured to the armature 15 75 are two angularly disposed arms 33 and 34, the arm 33 being normally in engagement with the pawl 28 and the arm 34 with the pawl 31. The energization of the magnet 6 withdraws said arms from engagement with 80 the respective pawls, permitting said pawls to engage said ratchet wheel to rotate it in one direction. A coiled actuating spring 35 is provided for returning said ratchet wheel to normal position when it is wholly 85 released. Springs 38 and 39 are adapted to return said arms 27 and 34 to normal position when the magnets are deenergized.

Referring now to the features of the device by means of which the objects of this 90 invention are obtained, same are as follows: Mounted upon a projecting lug 40 carried by the magnet frame is a flexible spring 41 having a projecting portion 42 thereon provided at its free end with a cup or semi-cylindrical portion 43. This spring 41 is in mechanical engagement with the arm 33 through an insulating knob 44 and is so tensioned as to partake of the movement of said arm 33. Carried by the ratchet wheel 29 are 95 two arms 47 and 48 each having a right-angled projection adapted to be brought into engagement with the cupped portion 43 of the spring 41. The arm 47 is insulated from the spring 41 preferably by means of 100 an insulating roller 49 mounted thereon, while the arm 48 is adapted to complete an electrical path through said spring when brought into engagement therewith. The length of the arms 47 and 48 is such with 105 110

relation to the movement of the spring 41 that when the holding magnet 6 is energized the projection on said arms will pass by on the right-hand or front side of the cupped portion 43 but will pass to the rear or left side thereof when the said holding magnet 6 is deenergized.

Referring now to Fig. 3 for the operation of a device embodying this invention, it will be borne in mind that stepping impulses and current impulses as applied in this description have distinct meanings. The first current impulse over the line when the magnets are deenergized will merely bring the stepping and holding pawls into engagement with the ratchet wheel, the second current impulse in this case being the first stepping impulse.

It will be assumed that the particular selector is one of a group of three, four or five or any other desired number, in all selectors of which group the insulated arms 47 will be brought into position to engage the springs 41 at the end of three stepping impulses sent over the line and the non-insulated arm 48 of the particular selector will be brought into position to engage the spring 41 in response to one additional stepping impulse over the line. The other selectors of the same group will have their arms 48 so arranged that they will be brought into contact with the spring 41 in response to different numbers of stepping impulses. If at the end of three stepping impulses current is removed from the line for a sufficient length of time to permit the slow acting holding magnet 6 to fall off, the movement of the arm 33 will permit the spring 41 to move into position to bring the cup portion 43 into engagement with the insulating roller 49 of the arm 47 and thus retain the ratchet wheel in a position of advance of three steps from normal. This will occur with all of the selectors of the particular group on the line but not with the selectors of any of the other groups, inasmuch as their arms 47 will be so adjusted that they will either be moved past their positions in which they engage their corresponding springs 41, or will not be far enough advanced to do so and, therefore, all other selectors will return to normal. If now two current impulses are again applied to the line, all of the selectors will be advanced one step which will bring the arm 48 of the particular selector shown of the selected group into position to be engaged by the contact spring 41 which will occur if the circuit at the sending station is opened for a period of time sufficient to permit the slow acting magnet 6 to fall off. The projection on the arm 48 coming into contact with the cup portion 43 on the spring 41 will hold the ratchet wheel 29 in that position and at the same time complete a local circuit

through a signal 50 including a local battery 51, the spring 41 and said arm 48. The selector will be released by applying a stepping impulse to the line to move the arm 48 out of engagement with the spring 41 and then removing current from the line.

The number of stepping impulses for moving the insulating holding arm of any group into position to be held should be odd and the number of stepping impulses necessary to move the non-insulated arm of any of the selected group into position should be odd, the total number of current impulses required to close any signaling circuit being even. This is for the purpose of preventing interference with the code numbers and to insure that only one selector closes its signaling circuit when a certain code impulse has been sent out. When both groups of steps are odd the total number of steps required to close any signaling circuit is even. Since only odd groups of stepping impulses are sent out, no single group of impulses will close a signaling circuit, but two groups of impulses are always required to accomplish this.

As an example of the difficulty which may be experienced in case this plan is not followed, assume that there will be one group in which the selector is advanced to its first hold position by three impulses and then into its signaling position by three succeeding impulses making a total of six for closing the signaling circuit of a particular selector. Taking another group, then, in which the selectors are advanced to their hold position by six impulses it will be obvious that each time the selector in this group is advanced to its hold position the selector in the group requiring six complete impulses to close its signaling circuit will be advanced to its signaling position. The same would be true of a selector in a group in which it required five preliminary impulses to advance it into its first hold position and an additional one to advance it into its second hold or signaling position. Clearly then, this interference may be avoided by making the total number of impulses necessary to close a signaling circuit an even number, and the number for stepping the selectors of any particular group into their first or preliminary position an odd number.

I claim:

1. In a selective signaling device, a step-by-step circuit-closing element, electromagnets for controlling the advancement of said circuit-closing element, angularly displaced projecting members carried by said step-by-step element, holding means controlled by said electromagnets for engaging one of said projecting members after said step-by-step element has been advanced a predetermined distance and said magnets are deenergized to hold said step-by-step element in an ad-

vanced position and engaging the other of said projections after a further advancement of said step-by-step element and the deenergization of said magnets, and a signaling circuit controlled by the engagement of the last of said projecting members with said holding means.

2. In a selective signaling device, a step-by-step circuit-closing element, electromagnets for controlling the advancement of said circuit-closing element, an insulated and a non-insulated projecting member carried by said circuit-closing element and separated from each other, a contact spring located adjacent said circuit-closing element and successively engaged by said projecting members in the movement of said circuit-closing element, the engagement of one of said projections with said contact spring holding said step-by-step element advanced when the said electromagnets are deenergized and the engagement of the other of said projections holding said circuit-closing element advanced and closing a signaling circuit.

3. In a selective signaling device a step-by-step circuit-closing element, electromagnets for controlling the advancement of said circuit-closing element, an insulated and a non-insulated arm carried by said circuit-closing element, a contact spring held out of the path of movement of said arms when said electromagnets are energized but adapted to be engaged thereby when said magnets are deenergized and said circuit-closing element has been moved predetermined distances to hold said circuit-closing element in its ad-

vanced position, and a signaling circuit closed by the engagement of said non-insulated arm with said contact spring.

4. In a selective signaling device, a step-by-step circuit-closing element, electromagnets for controlling the advancement of said circuit-closing element, separated projections carried by said circuit-closing element, and means controlled by one of said electromagnets upon the deenergization thereof after predetermined advancements of said circuit-closing element to successively engage said projections to hold said circuit-closing element advanced and a signaling circuit closed through said means and one of said projections.

5. A selective signaling device comprising a step-by-step circuit-closing element, stepping and holding magnets therefor, angularly separated arms carried by said circuit-closing device, a flexible contact member mounted to oscillate under control of said holding magnet, said contact spring being moved into engagement with said arms in predetermined positions of said circuit-closing element and upon the deenergization of said holding magnet, and a signaling circuit closed when one of said arms is in engagement with said contact spring.

In witness whereof, I hereunto subscribe my name this 28th day of March A. D., 1913.

JOHANNES P. C. BOSWAU.
